UNITED STATES PATENT OFFICE.

WILLIAM STEVENSON, OF CROMER, ENGLAND.

DESIGN FOR A FLOWER-POT PLATE.

SPECIFICATION forming part of Design No. 32,575, dated April 24, 1900.

Application filed August 21, 1899. Serial No. 728,039. Term of patent 7 years.

To all whom it may concern:

Be it known that I, WILLIAM STEVENSON, a subject of Her Majesty the Queen of Great Britain, residing at Cromer, England, have invented and produced a new and original Design for Flower-Pot Plates, of which the following is a specification, reference being had to the accompanying drawings, forming part thereof.

- This invention relates to an original design for flower-pot stands.

In carrying out my invention I form a square stand, and the upper surface of the stand is provided with grooves or channels which form a square parallel with the sides of the plate, and also grooves diagonally arranged in relation to the sides of the plate.

For purposes of illustration I will now refer to the annexed drawings, in which—

Figure 1 is a plan view of the stand, and Fig. 2 a section through line X Y in Fig. 1.

a is the square stand, being provided with recesses or grooves b, forming a square and running parallel to the sides of the stand and inclosing four grooves diagonally placed in relation to the sides of the stand, (marked b'.)

Having thus described my invention, what I claim, and desire to secure by Letters Patent, is—

The design for a flower-pot plate as herein shown and described.

WILLIAM STEVENSON.
